D. Anthony Davis

UNITED STATES PATENT OFFICE.

ERNEST WILLIAMS, OF NEW YORK, N. Y., ASSIGNOR TO METROPOLITAN DEVICE CORPORATION, OF BROOKLYN, NEW YORK, A CORPORATION OF NEW YORK.

CABLE-IDENTIFICATION TAG.

Application filed March 13, 1928. Serial No. 261,207.

This invention relates to an improved tag adapted for use in identifying electric feeder cables.

Heretofore it has been the common practice to secure a metallic tag to the various electric feeder cables located for example in street manholes. As many as twenty or thirty different cables may pass through a single manhole. The cables or feeders for the distribution of light or power carry high tension currents and are usually covered with a sheath. In order to identify the different cables the former practice in this art has been to loop a piece of wire carrying a metal tag around the sheath, said piece of wire having a porcelain insulating knob secured to one end. The metallic tags have therefore come into extensive use by power companies. But these metallic tags while serving very well for the purpose of identifying cables are open to the serious objection that when workmen enter a manhole or while making repairs or changes in the distribution layout they frequently strike the tags and produce a short circuit through a metal tag and its hanger on one cable to a tag and hanger on another cable.

While theoretically the lead sheaths of feeder cables are supposed to be electrically dead, in practice there is a constant current leakage and the lead sheaths carry this current. It is these stray currents that produce short circuits by the striking of one metallic identification tag against another. This is dangerous because it causes arcing in the manhole in which gases are sometimes accumulated, but the more serious objection is that each time there is an arc-over between ordinary identification tags there is a similar arc between the suspension wire and the lead sheath of the cable from which the tags are suspended. Repeated arcing caused by short circuiting through the identification tags pits the sheath and in due time flaws occur therein. Such flaws in the lead sheath permit short circuits of the power current and are extremely hazardous in the distribution of electric power.

The lead sheaths not only carry currents set up by leakage from their own conductors but they carry sometimes a certain induced current and also current from other sources such as the ground return from street railways, etc. The troubles are aggravated by the fact that in many electrical systems one side of an electric generator circuit is ground-

ed. The various stray currents therefore flow to the sheaths of power cables and any arcing over of these currents from a sheath of one cable to a sheath of another tends in time to disintegrate the sheath. I have discovered that this arcing over because of contact made by metallic identification tags on adjacent cables is a frequent though not generally recognized cause of failure of cables.

To overcome the disadvantages of prior practice I have devised an improved identification tag which includes a disk made of metal which can be readily embossed the disk being so supported with respect to the suspension wire by which it is secured to the cable that said identification tag can not possibly come into electrical contact with an adjacent tag and therefore my tag will not be instrumental in completing objectionable short circuits. Two embodiments of the invention are illustrated in the accompanying drawing in which

Fig. 1 is a sectional view showing a pair of juxtaposed cables provided with identification tags embodying my invention.

Fig. 2 is a detail of one of my tags ready for application to a cable.

Fig. 3 is an enlarged longitudinal section through the tag showing a preferred form of the invention.

Fig. 4 is a face view thereof partly in section.

Fig. 5 is a detail view of a metallic disk having identifying indicia thereon.

Fig. 6 illustrates a modification of identification tag in which the tag is adapted to be secured to existing forms of insulators the seal having an interrupted portion so that there is no contact between the metal part and the suspension wire.

Fig. 7 is a section on line 7—7 of Fig. 6.

Referring in detail to the drawing 10 represents sheathed electrical conductors such as used in the distribution of electric power. These conductors are usually enclosed in underground conduits. And in large cities it is well known that at various intervals manholes are provided in streets so as to give access to the feeder cables for the purpose of inspection and repair, testing for open circuits and so forth. It is necessary of course where many conductors pass through a manhole to have an identification for each cable. Heretofore this identification has been secured by passing a piece of wire around the 110

lead sheath of each cable and then threading a metallic identification tag on the wire and securing the end of the wire within a porcelain disk of known construction. As above indicated the metallic tags form an all too convenient path for short circuits or stray currents and such stray currents cause arc-overs which in time cause a pitting of the cable sheath.

10 Instead of applying a loose metallic tag directly to the suspension wire I provide a metallic disk 12 having suitable indicia embossed thereon such as numbers indicated at 14 and isolate the disk from the suspension 15 wire. As shown in Fig. 3 the metallic disk is held within a recess 16 formed in the tag body 18 of porcelain or similar insulating material. The disk 12 is preferably somewhat dished and is provided with one or 20 more recesses on its periphery as indicated at 20 so that merely pressing the thumb against the center of the disk it can be sprung into place behind shoulder 22 formed in the insulator body 18. To facilitate insertion of the disk the insulator is preferably formed with a flared or tapering mouth as indicated at 24. The body 18 is provided with suitable slots 26 either of which is adapted to receive a hooked end 28 of a suspension wire 30 which passes around the sheath of the cable. The opposite end of the suspension wire is formed with a hook 32 which is adapted to be bent around suspension member 30 as indicated in Fig. 1 so as to detachably secure the tag body 18 carrying disk 12 to a feeder cable.

It is clear that as thus arranged even though the tags 18 are swing about and strike one another, as indicated in dotted lines in 40 Fig. 1, there can be no electric connection between them because each metallic disk 12 is embedded within the outlines of the dielectric tag body 18 and is isolated from and is in no way connected with the suspension wire 30. In prior practice the metallic tags were merely threaded on to suspension members 30 and when they were jostled about of course formed an all too convenient path for short circuiting currents.

50 In Figs. 6, 7 and 8 the tag is in the form of a cup-like member 35 which is adapted to be pressed over a known type of insulator body 37. In this form of device the tag is

formed with an annular flange 34 which however is cut away at 36 so as to avoid any chance of contact between it and the suspension wire 30. Even though two adjacent tags of this type happen to contact with one another there will be no short circuit because there is no path by which the current can flow from the suspension wire 30 to the metallic tag.

Various other modifications may be made by those skilled in the art without departing from the invention as defined in the following claims.

What I claim is:

1. An article of manufacture comprising a cable identification tag including a dielectric body having a shouldered chamber formed with an outwardly flaring mouth and an identification disk held in sprung engagement behind the shoulder of said chamber.

2. An identifying means for electric cables comprising a dielectric body having a metallic identifying member held in sprung engagement therewith, a suspension member secured to said body but isolated from said metallic member, said body having a slotted portion and said suspension member having one extremity held therein and the other extremity formed with a hook portion.

3. An identifying means for electric cables comprising a dielectric body having a metallic identifying member secured thereto, a suspension member secured to said body but isolated from said metallic member, said body having a slotted portion and said suspension member having one extremity held therein and the other extremity formed with a hook portion.

4. An identifying means for electric cables comprising a dielectric body having a metallic identifying member secured thereto, a suspension member secured to said body but isolated from said metallic member, said body being recessed for engagement with one extremity of said suspension member, the opposite extremity of said suspension member being adapted for interengagement with another portion thereof.

In witness whereof, I have hereunto signed my name.

ERNEST WILLIAMS.
